his attys.

UNITED STATES PATENT OFFICE.

JAMES H. RAND, OF NORTH TONAWANDA, NEW YORK, ASSIGNOR TO RAND KARDEX COMPANY, INC., OF NORTH TONAWANDA, NEW YORK, A CORPORATION OF DELAWARE.

INDEX.

Application filed September 2, 1921. Serial No. 497,875.

This invention relates to indexes of the so-called visible index type in which a series of overlapping cards or sheets are supported on a frame by hinge connections; and the invention consists more particularly in the novel and improved construction of the hinge connection and its associated parts hereinafter described and pointed out in the claims.

10 In the accompanying drawings which illustrate the invention,—

Fig. 1 is a front view of part of an index embodying the invention;

15 Fig. 2 is an enlarged, vertical cross section on line 2—2 of Fig. 1;

Fig. 3 is a front view of one of the folded index sheets and its rail and hinge connections, the front leaf of the sheet being swung forwardly and upwardly to show the hinge 20 connections;

Fig. 4 is an enlarged cross section of a detail on line 4—4 of Fig. 3; and

Fig. 5 is a similar cross section showing a modification.

25 The frame of the index may be of usual construction and as herein shown is made of sheet metal and consists of a back 6 and infolded marginal flanges 7, which form channels to hold the ends of the rails to 30 which the index cards or sheets are hinged.

In the form shown in Figs. 1 to 4 inclusive, the rails 8 consist of strips of bristol board or other suitable material having sufficient resiliency to be sprung into the frame 35 as shown in Fig. 1.

Mounted on the rail 8 are one or more card or sheet supporting members 9 (a pair being shown in the drawings) which are preferably made of a piece of sheet metal bent 40 to form a body part extending across the face of the rail with its ends 10 bent over to embrace the longitudinal edges of the rail, and its middle part bent forwardly to form a projecting loop 11 which constitutes 45 a hinge member as hereinafter explained. These sheet-supporting members are mounted to slide lengthwise of the rails so as to be readily adjustable to any desired position thereon.

50 Each index card or sheet 12 is folded on itself, and a slot or aperture 13 is cut in the sheet along the line of its fold, one for each sheet-supporting member. The for-

wardly projecting loop or hinge member 11 extends through the aperture, and the card 55 or sheet is separably attached to the sheet-supporting members by a wire 14 inserted through the loops 11. The wire 14 constitutes both a fastener by which the sheet is locked to the supporting member, and a 60 pintle, or second hinge member, by which the sheet is pivotally attached to the supporting members and to the rail. The ends of the wire 14 may then be bent to prevent it from becoming accidentally displaced. 65

By having the supporting members 9 adjustable on the rails, the slots or apertures may be formed in the cards or sheets without requiring close measurement or positioning to insure a fit, and the supporting members may then be adjusted until they come opposite the apertures; the parts may then be readily assembled as shown. This makes it possible in attaching or replacing index cards or sheets for unskilled users to apply 75 cards which they may already have on hand to the frame, and to make the necessary apertures without too great attention to precision. Obviously the apertures 13 may be placed in any position along the fold 15 80 of the sheet, and the supporting members adjusted accordingly.

In the modification shown in Fig. 5 the rail 16 instead of being a solid strip of sheet material, is of hollow or tubular formation. 85 It may be made of any suitable sheet material such as sheet celluloid, with its longitudinal margins 17 bent forwardly and inwardly, leaving a slot between them. The supporting member comprises the body plate 90 18, which slides in the tubular rail, and the forwardly projecting loop or hinge member 19 which extends through the slot between the bent-over margins 17. The card or sheet 12 is fastened and hinged as before 95 by the pintle 14 which passes through the loop 19.

I claim:

1. An index including spaced parallel guides, rails slidable in the guides, said rails being supported by lateral engagement one with the other, supports slidably mounted on the several rails and having projecting loops, intermediately folded sheets having apertures receiving the loops and fastener 105 members engaged in the projecting portions

of the loops and the fold of the sheets to secure individual sheets to their respective rails.

2. An index including spaced parallel guides, rails slideable in the guides, said rails being supported by lateral engagement one with the other, supports slideably mounted on the several rails and having projecting loops, intermediately folded sheets having 10 apertures receiving the loops, fastener members engaged in the projecting portions of the loops and the fold of the sheets to secure individual sheets to their respective rails, said fasteners comprising rods extending 15 transversely of the sheets and having bent terminal portions securing the parts in assembled relation.
3. An index including spaced guides, rails

having terminal portions slidably mounted in the guides, said rails bearing supports 20 adjustably mounted thereon and having projecting loops, folded sheets having apertures receiving the loops, the width of the sheets being substantially that of the space between the guides, fastener members engaging the 25 loops and the inner face of the fold for securing the sheets to the supports whereby the sheets are held for pivotal movement between the guides, the loops of the several rails being spaced from each other, whereby 30 the lower edge of each sheet depends below the edge of the sheet carried by the rail thereabove.

Signed by me at Boston, Massachusetts, this 31st day of August, 1921.

JAMES H. RAND.
